UNITED STATES PATENT OFFICE.

JOHN W. ENRIGHT, OF NEW ORLEANS, LOUISIANA.

STATIONARY CHEMICAL-MIXING FIRE-EXTINGUISHER SYSTEM.

1,353,466.

Specification of Letters Patent. Patented Sept. 21, 1920.

Application filed March 10, 1919. Serial No. 281,691.

To all whom it may concern:

Be it known that I, JOHN W. ENRIGHT, a citizen of the United States of America, residing at New Orleans, in the parish of Orleans and State of Louisiana, have invented certain new and useful Improvements in Stationary Chemical-Mixing Fire-Extinguisher Systems, of which the following is a specification.

10 This invention relates to stationary chemical mixing fire extinguisher systems.

The invention relates to a system which is devoid of moving mechanical parts and operates automatically under fire emergency 15 conditions and the objects of the invention are to insure the prompt and certain automatic operation of the system and to insure a regular and continuous supply of acid to the alkaline solution, thereby providing for 20 the discharge of substantially the entire volume of alkaline solution at a substantially uniform pressure.

An embodiment of the invention is illustrated in the accompanying drawing where- 25 in the figure is a diagrammatic sectional view of a fire extinguisher system in which the features of the invention are incorporated.

The system includes the usual tank 1 for 30 an alkaline solution and a riser 2 extending from said tank throughout the height of the building, said riser being connected to the usual leaders or laterals 3 which carry sprinkler heads or distributing valves 4.

35 The system also includes an acid receptacle 5 which is preferably arranged in an extension 6 of the tank 1, located at the upper side thereof. The receptacle 5 incloses an acid discharge pipe 7 having at its up- 40 per end a gooseneck discharge terminal 8 projecting externally of said receptacle and discharging into an acid reservoir 9. The reservoir 9 discharges into the tank 1 by a pipe 10 in which is arranged a mercury seal

45 11 whose function is to prevent the acid from passing into the tank until a predetermined quantity, necessary to overcome the mercury of the seal, shall have been trapped in the reservoir 9, such quantity being suffi- 50 cient to insure the prompt and effective initial discharge of the fire extinguishing liquid at the open sprinkler head or distributing valve.

The discharge of acid from the receptacle 5 is effected by pneumatic pressure which is transmitted to the upper portion of said

receptacle by a pipe 12. The pipe 12 is arranged vertically and projects for some distance into the tank 1, being connected at its lower end to a vertical pipe 13. The pipes 12-13 form a U-tube and the pipe 13 projects beyond the extension 6 and has at its upper end a return bend 14 which communicates with the interior of said extension. The projecting portion of the pipe 13 is also 65 connected by a branch pipe 15 to a mercury vessel 16 from which rises a vertical tube 17, whose lower end dips into the mercury in the vessel 16. Above the vessel 16 the tube 17 is connected by a branch pipe 18 to 70 a reservoir 19 for a liquid medium, in this instance mercury, a manually operated valve 20 being arranged in the pipe 18.

After the tank 1 has been filled with the requisite quantity of alkaline solution and 75 mercury has been placed in the seal 11 and in the vessel 16 and reservoir 19, the valve 20 being closed, the system, i. e. the tank and the distributing system, is charged in any suitable way with air or gas under the 80 pressure desired, e. g., twenty pounds, and such pressure is effective to displace the mercury in the vessel 16, i. e., to force a column of mercury into the tube 17 to a point above the pipe 18. The valve 20 is 85 thereupon opened and the system is ready for operation, it being noted that the pressure with which the system is charged is transmitted by the pipes 13-12 to the interior of the receptacle 5. 90

When a sprinkler head or distributing valve 4 is opened under fire emergency conditions, the pneumatic pressure in the system of course starts to fall with the result that the mercury column in the tube 17 falls 95 below the pipe 18 and the mercury in the reservoir 19 flows through the tube 17 to the receptacle 16 and overflowing the latter passes by the pipe 15 to the pipe 13, in which, and the pipe 12, it forms a seal be- 100 tween the interior of the receptacle 5 and the interior of the tank. By virtue of such seal any further reduction of the pneumatic pressure consequent to the escape of the air or gas at the open valve 4 is not transmitted 105 to the receptacle 5, and the pressure being thus unbalanced, it follows that the greater pressure in the receptacle 5 will cause an initial discharge of acid therefrom, sufficient in quantity to fill the reservoir 9 and over- 110 come the seal 11. The high pressure generated consequent to the mixing of the chemi-

- cals passes by the pipe 7 to the receptacle 5 in which it is trapped and becomes effective to eject a further quantity of acid as soon as the pressure in the tank starts to fall. In 5 this way the operation of the system is maintained continuously and at a substantially uniform rate of pressure until the receptacle 5 is practically exhausted of its acid contents.
- 10 It will be noted that the system does not go into operation until a predetermined degree of pneumatic pressure has been discharged therefrom, the degree of pressure at which the system operates being determined 15 by the position at which the reservoir 19 connects to the tube 17; this connection may be made at a height suitable to allow the pneumatic pressure to fall to two pounds before the mercury column in tube 17 falls 20 below the pipe 18, thus allowing a considerable range in the degree of pressure, in order to provide against accidental operation of the system through leakage of the pneumatic pressures. Any approved low pressure 25 alarm may be used to signify when the pneumatic pressure has fallen by leakage to near the point of operation, and the system may then be pumped up again.
- Having fully described my invention, I 30 claim:—
1. In a chemical mixing fire extinguisher system, a tank for an alkaline solution, an acid receptacle, a discharge pipe inclosed within said receptacle and discharging at its 35 upper end into said tank, said discharge pipe also transmitting the developed high pressure from said tank to said receptacle, a pair of pipes forming a U and one of which is connected at its upper end to said receptacle, a distributing system adapted to normally contain an elastic fluid medium, a 40 mercury vessel, a tube projecting therefrom, a receptacle for a liquid medium connected to said tube and an outlet connection between said mercury vessel and the other pipe 45 of said pair, the fluid medium in the distributing system normally maintaining a mercury column in said tube which prevents the flow of the liquid medium from the 50 receptacle therefor.
2. In a chemical mixing fire extinguisher system, a tank for an alkaline solution, a distributing system connected to said tank and normally containing an elastic fluid 55 medium, a vessel containing mercury under the normal control of said fluid medium, a pair of pipes forming a U, an outlet connection between the mercury containing vessel and one of the pipes, a receptacle for a 60 liquid medium which passes to said pipes under fire emergency conditions, an acid receptacle to which the other of said pipes is connected at its upper end, a discharge pipe inclosed within said acid receptacle 65 and discharging at its upper end into said

tank, said discharge pipe also transmitting the developed high pressure from said tank to said acid receptacle and a tube extending from said mercury containing vessel and in which a column of mercury is normally maintained by said fluid medium, and an outlet connection from said liquid medium receptacle to said tube below the normal mercury level in the latter.

3. In a chemical mixing fire extinguisher 75 system, a tank for an alkaline solution, a distributing system connected to said tank and normally containing an elastic fluid medium, a vessel containing mercury under the normal control of said fluid medium, a 80 pair of pipes forming a U, an outlet connection between the mercury containing vessel and one of the pipes, a receptacle for a liquid medium which passes to said pipes under fire emergency conditions, an acid 85 receptacle to which the other of said pipes is connected at its upper end, a discharge pipe inclosed within said acid receptacle, said discharge pipe also transmitting the developed high pressure from said tank to 90 said acid receptacle, a tube extending from said mercury containing vessel and in which a column of mercury is normally maintained by said fluid medium, an outlet connection from said liquid medium receptacle to said 95 tube below the normal mercury level in the latter and an acid reservoir into which the acid passes from said discharge pipe, said reservoir having a mercury sealed outlet to said tank.

4. A fire extinguisher system including a fire extinguisher agent supply means having normally communicating elements for maintaining elastic fluid under pressure, a piping system connected with one element, 105 a distributing valve in said piping system, means operative under fire emergency conditions for automatically sealing the communication between said elements, thereby to trap a portion of the elastic fluid under 110 pressure in one of said elements, and means set in operation by the trapped elastic fluid for causing the operation of the fire extinguishing agent supply means when the remaining elastic fluid, by its escape through 115 said valve, is reduced in pressure below the trapped fluid.

5. A stationary chemical mixing fire extinguishing system including a solution tank and an acid receptacle, both adapted to contain elastic fluid under pressure, a normally open means of communication between the elastic fluid-maintaining spaces of said tank and receptacle, means operative under fire emergency conditions for reducing the pressure of the elastic fluid in said tank, means operative on the reduction of pressure in said tank for sealing the communication between said tank and said receptacle, thereby to trap a portion of the elastic fluid in 130

said receptacle, and a pipe for discharging the acid from said receptacle into said tank and through which the acid is initially forced by the fluid trapped in said receptacle.

6. In a stationary chemical fire extinguisher system, a solution tank and an acid receptacle, both adapted to contain elastic fluid under pressure, a normally opened communication between the elastic fluid of said tank and receptacle, means operative under fire emergency conditions for reducing the pressure of the elastic fluid in said tank, means operative on the reduction of pressure in said tank for sealing said communication between the tank and receptacle, thereby to

first trap a portion of the elastic fluid in said receptacle for initiating the discharge of acid therefrom for generating high pressure gases, and thereafter for trapping the developed high pressure gases in said receptacle, and a pipe for discharging acid from said receptacle to said tank and through which the high pressure gases pass to said receptacle.

In testimony whereof I have hereunto set my hand in presence of two subscribing witnesses.
